UNITED STATES PATENT OFFICE

EDGAR GEORGE WEBSTER, OF PECKHAM, LONDON, ENGLAND, ASSIGNOR TO HYGIENIC
WIRE WORKS LIMITED, OF LONDON, ENGLAND

BIRDCAGE STAND

Application filed April 4, 1932, Serial No. 603,066, and in Great Britain October 23, 1931.

Birdcages which are provided with a loop at their upper ends for suspension to a chain or cord, are suitable also for suspension in a stirrup frame carried on a stand, which 5 for convenience may be detachable in several sections. Such stands usually consist of a foot portion with a standard which may screw into the foot portion and have an extension on the upper portion of the standard, 10 and at the upper portion of such extension a branched stirrup frame has been used which branches upwards and connects over a suitable enclosed arch within which the cage is suspended.

15 The object of this invention is to dispense with this stirrup frame and to provide convenient means at the top of the extension or standard for supporting the cage on its base.

20 According to this invention, at the top of the extension a fitting is attached having four recessed sockets, into which rods may be inserted at predetermined angles so as to radiate outwards and upwards. The rods are 25 of such a length and are directed at such angles, that the outer ends of these rods are located in positions approximating to the interior hollow feet below the base plate of the cage to be supported. The weight of the 30 cage is borne by the rods and tends to expand their ends away from the centre, thus causing a binding-fit between the rods and the interior of the cage. Alternatively, the rods instead of being detachable, may be pivoted to the top of the extension. This 35 fitting may also be attached to the extension so as to rotate thereon, and in this event it is suitably made in the form of an inverted cone, the walls of which may be in line with the angular direction in which the 40 rods are to be held.

The invention will now be described with reference to the embodiment illustrated upon the accompanying drawings, in which:—

45 Fig. 1 is a sectional elevation of a stand constructed in accordance with this invention, showing a birdcage mounted on the top of said stand, the base portion only of the birdcage being shown in longitudinal 50 section.

Fig. 2 is an inverted plan view partly in section on the line 2—2 in Fig. 1.

Fig. 3 is a section of a fragment of the stand on the line 3—3 in Fig. 2.

Fig. 4 is a perspective view of the cage 55 and upper end of the stand.

In the construction illustrated, the stand comprises a foot portion *a*, a standard *b* screwing into the foot portion, a fitting *c* and a screwed cap *d*. The fitting *c* is mounted 60 to rotate on a reduced shank *b*¹ and bears on the shoulder *b*² at the upper end of the standard. The reduced shank *b*¹ is provided with a screwed projection *b*³ on which screws the 65 cap *d* serving to retain the fitting *c* in position on the standard. The fitting *c* is formed with four sockets *c*¹, *c*², *c*³, *c*⁴, said sockets receiving four rods *e*¹, *e*², *e*³, *e*⁴ and being so arranged that when inserted in said sockets, the rods *e*¹, *e*², *e*³, *e*⁴ radiate outwards and upwards. Said rods are made slightly flexible or are otherwise so arranged that their outer 70 ends *e*⁵, *e*⁶, *e*⁷, *e*⁸ can be contracted towards the centre from which they radiate. Further, these rods are so arranged that when contracted their outer ends *e*⁵, *e*⁶, *e*⁷, *e*⁸ are located in positions approximating to the interior of the hollow feet *f*¹, *f*², *f*³, *f*⁴ below the 75 base plate *f* of the cage indicated generally by *g*. When the outer ends of said rods are entered in said hollow feet, the weight of the cage is borne by the rods and this tends to extend their ends away from the centre from which they radiate, thus causing a binding-fit between the rods and the cage.

80 By making the rods and other parts as described, these can be detached to facilitate storage, transport and replacement.

85 It will be recognized that in the arrangement according to this invention, the centre of gravity of the stand and cage is considerably lower than in the case where a stirrup frame is carried over the upper part of the cage and the cage is suspended to such stirrup. It is also less complicated and therefore more artistic in appearance, while the security afforded by the outer ends of the rods being contained and binding within the hollow feet, is a considerable advantage in 90 95 100

stands which are required to support birdcages at a distance above the floor.

What I claim as my invention and desire to secure by Letters Patent is:—

- 5 1. The combination of a birdcage stand, a rotatable fitting on the top of said stand, and flexible rods radiating upwardly and outwardly from said fitting, said rods having their outer ends adapted to be entered into
- 10 hollow feet below a cage to be supported and adapted to expand under the weight of the cage in order to secure a binding-fit in said feet.
- 15 2. The combination of a birdcage stand, a fitting on the top of said stand, a birdcage having hollow feet, and flexible rods radiating upwardly and outwardly from said fitting and entering into said hollow feet with a binding-fit.
- 20 20 In witness whereof I have hereunto set my hand.

EDGAR GEORGE WEBSTER.
